ELECTION GAME

William C. Sanford, La Oroya, Peru

Application April 21, 1938, Serial No. 203,433

3 Claims. (Cl. 273—131)

The present invention relates to a game and more particularly to a game of the board and movable piece type.

An object of the present invention is to provide, in a game, equipment which shall include suitable characteristics indicative of the political instrument known as the electoral college, whereby the play may ordinarily proceed in simulation of the statistical progress of a national election under the current two-party system.

In one embodiment, the game includes apparatus consisting of a board and a plurality of pieces, the board presenting a checkered field of inner and outer areas for play and the pieces bearing distinguishing indicia. The pieces are designed for play on the board and consist of two groups, the larger consisting of game pieces approximating in number the number of political divisions embraced in the election, and the smaller group including player pieces representative of two major contestants for election and through manipulation of which the action of the game is realized.

Other objects of the invention will be apparent from the following description of a preferred form, taken in connection with the accompanying drawing forming part thereof, wherein:

Fig. 1 is a plan view of a game board capable of utilization in the invention;

Fig. 2 is a perspective view of a typical game piece, it being understood that 48 thereof may be utilized in the game;

Fig. 3 is a perspective view of one of the player pieces, same being lined for color (blue); and

Fig. 4 is a corresponding view of the other player piece, same being lined for red.

Referring to the drawing, board 10 shown in Fig. 1 is square, having ends 11 and 12 and opposite sides 14 and 15. The playing surface 16 of the board consists of a plurality of squares 17, defined by a series of equally spaced longitudinal lines 18 and transverse lines 19.

Lines 18 and 19 define, in the present embodiment, 225 squares or 15 squares along each dimension of the board. The majority of the squares are blank, the balance being arranged in an inner area in horizontal rows and many of which bear indicia to indicate the initial position of the State tokens or game pieces. For example, row 21 contains 4 marked squares designating the States of Idaho, Arizona, Delaware, and Montana. Row 22 contains four marked squares designating, respectively, the States of South Dakota, Wyoming, Vermont, and Utah. Rows 23, 24, 25, 26, and 27 contain marked squares alter-

nating with blank squares and collectively marked to designate the remaining States of the Union. At opposite sides of the board there are provided outer areas or rows 29 and 30 composed of squares blank save for the middle square which is marked, as shown at 31 and 32, respectively, to indicate initial positions for player pieces 33 and 34 (Figs. 3 and 4).

The arrangement of the board is based upon the discovery that the States of the Union fall into seven groups, some of which groups resemble other groups as respects voting strength in the electoral college. By comparing the following tabulation of State voting strength with the indicia on rows 21 to 27, inclusive, it will be observed that the States may be arranged in groups capable of being paired as to voting strength.

State	Votes	State	Votes
<i>Row 21</i>		<i>Row 22</i>	
Idaho	4	South Dakota	4
Arizona	3	Wyoming	3
Delaware	3	Vermont	3
Montana	4	Utah	4
	— 14		— 14
<i>Row 23</i>		<i>Row 24</i>	
Arkansas	9	Kansas	9
Connecticut	8	Washington	8
Maryland	8	West Virginia	8
Florida	7	Nebraska	7
Maine	5	Colorado	6
Oregon	5	North Dakota	4
New Hampshire	4	Rhode Island	4
New Mexico	3	Nevada	3
	— 49		— 49
<i>Row 25</i>		<i>Row 26</i>	
New Jersey	16	Missouri	15
North Carolina	13	Indiana	14
Wisconsin	12	Georgia	12
Alabama	11	Oklahoma	11
Iowa	11	Tennessee	11
Kentucky	11	Virginia	11
Minnesota	11	Louisiana	10
South Carolina	8	Mississippi	9
	— 93		— 93
<i>Row 27</i>		<i>Row 28</i>	
Massachusetts	17		
Michigan	19		
California	22		
Texas	23		
Ohio	26		
Illinois	29		
Pennsylvania	36		
New York	47		
	— 219		

For example, row 21 and row 22 each contain four different States having a total of 14 electoral votes each. Rows 23 and 24 represent groups of States indicated whose electoral votes total 49. Rows 25 and 26 represent groups of States, each group representing 93 electoral votes. The disposition of rows 21 to 26, inclusive, on the board

is such that States of corresponding voting strength are substantially equidistant from the marked player squares 31 and 32. For example, States appearing in each of lines 21 and 22 5 possess a voting strength of 14. States in each of rows 23 and 24 possess a voting strength of 49. Those States appearing in rows 25 and 26 have a total strength of 93. Row 27 is equidistant between initial player positions 31 and 32. The 10 voting strength of the States included in row 27 is 219, thus giving each contestant an equal opportunity to capture such valuable territory.

Essential to the practice of the game are State or game pieces 36. It will be understood that 15 the game includes 48 such pieces, each of which is marked to represent a different State of the Union and also to bear indicia to indicate the voting strength of that State in the electoral college. As shown, for example, in Fig. 2, the 20 game piece representing the State of New York bears numerals 47. By reference to the above tabulation, and particularly with the group listed under "Row 27", the voting strength of New York is stated to be 47. It will be understood, 25 by reference to said tabulation, that the Pennsylvania game piece will bear numerals 36 indicating that State's voting strength, the game piece representing the State of Illinois will bear numerals 29 indicating its strength, and 30 so on.

At the start of the game the player pieces 33 and 34 may be placed upon the initial player squares 31 and 32. The game pieces 36 are then distributed over the State squares according to 35 the marking of said squares, the Arizona game piece being placed upon the Arizona square, the Connecticut game piece on the Connecticut square, and such system followed until each game piece in the set rests upon its corresponding 40 square. The 48 squares inscribed with the symbols of the respective States serve only the purpose of indicating the location of the State pieces or tokens at the start of the game.

The object of the game for a contestant is to 45 win as many States as possible, or at least a sufficient number to achieve a majority of the electoral votes. When a player moves his party piece or token into any square then occupied by a State piece, such State is then considered to 50 have been won, and said player should remove the State piece from the board and credit his score with the number of votes (points) indicated on the State piece.

It will be observed that the location of the 55 State and party pieces at the start of the game, as described above, is extremely important because it insures the two contestants an equal chance, taking into consideration the segregation of the States into one pair of rows each 60 totaling 14 electoral votes, another pair of rows each totaling 49 electoral votes, still another pair having 93 votes each, and the single row 27 totaling 219 votes.

At the commencement of play, the board presents a field upon which each contestant may 65 endeavor, by moving any of the State pieces or his own player piece into a contiguous square, to capture States and thereby score as many points or electoral votes as possible.

70 Any method of lot may be used to determine which player shall be entitled to make the first move of the game, and preferably the players alternate in succeeding games in right to make the first move. After the first move, the players 75 alternate in moving, as in chess or checkers.

Various types of playing strategy may be employed; for example, a party token may be moved to approach a State token, to move into a square occupied by a State token to thereby capture it, to move into a commanding position over one or 5 more State tokens, or to block the strategy of the adversary. Except that it may not be moved into a square occupied by the adversary's party token, a party token may be moved one space at a time in any direction, forward or backward, to the right or to the left, across a side or a corner, and from any square to any adjoining square.

Except that it may not, before at least one intervening move, be moved back to the square 15 from which it was moved on the play just preceding, a State piece or token may be moved, one space at a time, in any direction, forward or backward, to the right or to the left, across a side or a corner, from any square to any unoccupied adjoining square. The exception stated is necessary to avoid a situation of stalemate arising when a State token is moved repeatedly back and forth between two squares. The purpose for moving the State tokens is to maneuver 20 them into position where the party token of the player will command them; that is, where the party token will be closer to them, in number of moves, than the party token of the adversary. A player may thus attempt to gain the command 25 over several State tokens before he moves his party token to effect their capture. State tokens also may be moved to extricate them from the command of the adversary, or into position to block the strategy of the adversary. 30

A player who captures sufficient State tokens or game pieces 36 to make a majority of the electoral votes (266) wins the game. When it is determined that a game has been won, the loser may elect to continue the play or, instead, to concede the remaining States to the winner. The game score of each player is credited with the sum of all the electoral votes indicated on the game pieces 36 captured by him and conceded to him, and also with a sum, as agreed upon, for each game won by him. 35

From the foregoing it will be observed that the present embodiment presents a game affording exceptional opportunity for the play of individual design and strategy, the rules of which are simple. A player may attempt to capture many little States or a comparatively few States having large numbers of electoral votes, such as, for example, the States in row 27 or those in rows 25 and 26. He may move his party token directly toward the State tokens, or he may move several State tokens into position where his party token commands them. On the other hand, the play may be a combination of the two methods. A player's moves also may be calculated to confound the adversary either, for example, by directly opposing his strategy or by screening the strategy of the player. Ultimately, the only element of chance encountered in playing the game is the human element; otherwise the game is 60 one of pure skill and intellectually stimulating, besides having the popular appeal of one resembling a presidential election campaign. For instance, I have found that chess players excel in this game, although it is not as difficult as chess and hence may be enjoyably played much more 65 easily than chess.

Although the present embodiment utilizes a particular arrangement of State squares on the board, it will be understood that their position 70

may be altered in detail without departing from the spirit of the invention. For example, the distribution of some of the low scoring States may be varied with respect to the player-starting squares 31 and 32. Or the player-starting squares may be moved toward the center without altering that desirable factor requiring that the starting positions of the players be equal with respect to the starting positions of State or game 10 tokens of commensurate value. Also, while certain of the squares on the board and the game pieces 36 have been designated by name of States and the numbers of electoral votes, these may have any other desirable designations thereon 15 without departing from the principle of the game and the manner of playing it, as above described.

I claim:

1. A game simulating a presidential election campaign comprising player tokens one for and 20 to be actuated by each contestant, one set of State tokens each representing a different State of the Union and each bearing indicia denoting a different State and to be actuated by either contestant, a game board having a surface for sup- 25 porting and over which said tokens may be moved, the board having at least a portion of its surface divided into contiguous squares or areas arranged to form substantially parallel rows which extend in directions substantially at 30 right angles to each other, like alternate areas of alternate rows bearing indicia referring to different States of the Union, such State areas corresponding in number with the number of said State tokens, said board having two oppo- 35 sitely disposed marginal areas from which the initial move of a player token is made, the areas representing States of minor voting strength being included in the outer of said rows of State areas adjacent the said marginal areas, the State 40 areas representing States of major voting strength being included in the rows between said rows of State areas of minor voting strength, each of said State areas constituting the initial location for its corresponding State token.

2. A game simulating a presidential election 45 campaign comprising player tokens to be actu-

ated by each contestant, a plurality of State tokens one representing each State of the Union and each bearing indicia denoting a different State, a game board having a surface for supporting and over which said tokens may be moved, the board having at least a portion of its surface divided into contiguous squares or areas arranged to form substantially parallel rows which extend in directions substantially at right angles to each other, like alternate areas of 10 alternate rows bearing indicia representing different States of the Union, such State areas corresponding in number with the number of said State tokens, said board having two oppositely disposed marginal areas from which the initial 15 move of a player token is made, one of said State rows between said marginal areas being a State middle row and representing States of major voting strength, the State areas in rows on opposite sides of the middle row representing States 20 of progressively lesser voting strength toward said marginal areas, each of said State areas constituting the initial location for its corresponding State token.

3. A game simulating a presidential election 25 campaign comprising a player token to be actuated by and for each contestant, a plurality of State tokens one representing each State of the Union and each bearing indicia denoting a different State and to be actuated by either contestant, 30 a game board having a surface for supporting and over which said tokens may be moved, the board having at least a portion of its surface divided into contiguous squares or areas arranged to form substantially parallel rows in 35 directions substantially at right angles to each other, like alternate areas of alternate rows bearing indicia referring to different States of the Union, whereby each State area is separated from an adjacent State area by a blank area, such State 40 areas corresponding in number with the number of said State tokens, each board having two oppositely disposed marginal areas from which the initial move of a player token is made.
